UNITED STATES PATENT OFFICE.

HENRY HOWSON, OF PHILADELPHIA, PENNSYLVANIA, ASSIGNOR TO JOHN L. KITE, OF SAME PLACE.

TELEPHONIC APPARATUS.

SPECIFICATION forming part of Letters Patent No. 238,689, dated March 8, 1881.

Application filed January 18, 1881. (No model.)

To all whom it may concern:

Be it known that I, HENRY HOWSON, a citizen of the United States, residing in Philadelphia, Pennsylvania, have invented an Improvement in Telephonic Apparatus, of which the following is a specification.

My invention consists in combining a movable receiver, a transmitter, and switch of telephonic apparatus with mechanism through the medium of which the switch is automatically operated in adjusting the receiver to and releasing it from contact with the ear of the operator, the mechanism being such that both hands of the operator are at liberty while he is receiving and transmitting messages.

In the accompanying drawings, Figure 1, Sheet 1, is a front view of telephonic apparatus with my improvements; Fig. 2, a plan view of Fig. 1; Fig. 3, a view of a receiver, which may be used in connection with my improvements; Figs. 4, 5, and 6, views representing a modification of my invention; and Figs. 7 and 8 are views of further modifications.

It may be stated in the outset that the devices through the medium of which the receiver of telephonic apparatus is combined with the switch to bring about the desired result admit of many variations, the character of the appliances used depending partly on that of the telephone and partly on its locality. In Figs. 1 and 2, for instance, an ordinary Bell-telephone box, A, and a microphone transmitter, B, are secured to the wall D, near the corner of a room, of which D' represents another wall built at right angles to the wall D.

The receiver E, which may be of the style shown or of any of the styles, is carried by an arm, F, on a shaft, G, which is adapted to bearings on a board, b, secured to the wall D'; or the bearings may be attached directly to the said wall, the arm being near one end of the shaft, and another arm, H, being secured to the other end of the shaft, and being in such a position that it will bear on the switch-arm I of the telephone when the receiver and its arm F are in the position shown by plain lines in Fig. 1. This arm I is the same as that from which the ordinary receiver is usually suspended, when the telephone is not in use, the weight

of the receiver depressing the switch-arm and keeping the telephonic circuit disconnected, and the circuit being established whenever the arm I is relieved from the weight of the receiver.

It is to avoid the necessity of holding the receiver in the hand while messages are transmitted and received which constitutes the main object of my invention.

When the arm F has been raised to the position shown by dotted lines in Fig. 1, the flaring end of the receiver will be in a proper position for the ear of the operator, whose mouth is directly in front of and at an appropriate distance from the transmitter, and by a slight pressure of his ear against the receiver he can maintain the latter and the arm in an elevated position, and the arm H so far above the switch I that the circuit will be connected for receiving and transmitting messages; but when the operator, by withdrawing his head, releases the receiver and arm, they will fall to the position indicated by plain lines, and the circuit will be disconnected, owing to the depression of the switch by the arm H.

The arm F is preferably made adjustable on the rod, both circumferentially and longitudinally, so that when the receiver is applied to the ear of the operator his mouth may be in a proper position in respect to the transmitter. It is also advisable to make the receiver E adjustable on the end of the arm F, which, in the present instance, is provided with a clamp for grasping the said receiver.

The arm F and its receiver may be so counterweighted that a very slight pressure of the ear against the receiver will serve to maintain it and its arm in an elevated position; but, if desired, the receiver may be provided with a projection, n, Fig. 3, for resting on the ear, as shown in Fig. 3.

In order to obviate a shock when the arm and receiver are released, I prefer to make the arm H slightly elastic by bending it, as shown; or a spring may be interposed between a rigid arm, H, and the switch, either by securing it to the former or to the latter.

It will be seen that after the first adjustment of the receiver to the ear of the operator both his hands will be at liberty during the

transmission and reception of messages, and consequently that he will be enabled to write at a properly-situated desk, W, with the same ease and comfort as at an ordinary desk.

5 In Figs. 4, 5, and 6 a telephone is situated against a wall, at such a distance from the corner of the room that the above-described appliances cannot be used to advantage; hence I pivot a receiver-carrying arm, F, to bearings 10 which are secured to the board to which the telephone-box A, transmitter B, and desk W are attached, a rod, m, being joined at its lower end to the arm F, the end of the switch-arm I passing through a slot in the upper portion 15 of the said rod. A spring is contained within the slot at the upper end of the rod, so as to absorb the shock when the arm is released, and the spring or a washer beneath the same is brought into violent contact with the switch 20 and depresses the same.

As remarked above, different appliances may be used for causing a movable receiver to operate the switch. In Fig. 7, for instance, the receiver is carried by a rod arranged to slide 25 freely in the socket t, from which the rod must be partly withdrawn to adjust the receiver to the ear of the operator, whose mouth is op-

posite to the transmitter, the rod, which may be partly counterbalanced, falling when released, and striking the lever K, to which a 30 rod similar to that shown in Fig. 5 is connected.

In Fig. 8 a treadle is used for raising the receiver to the ear of the operator, who is stationed in a proper position in respect to the 35 transmitter. The devices for insuring the automatic action of the switch may, in this case, be the same as in Fig. 5.

I claim as my invention—

In telephonic apparatus, the combination of 40 a transmitter, a switch, a receiver, and a support for the same, with mechanism whereby the receiver may be held to the ear without the aid of the hands, and whereby the switch is automatically operated on adjusting and releasing the receiver, all substantially as described.

In testimony whereof I have signed my name to this specification in the presence of two subscribing witnesses.

HENRY HOWSON.
